Inventor:

UNITED STATES PATENT OFFICE.

ERI GRAHAM, OF LANCASTER, WISCONSIN, ASSIGNOR OF TWO-THIRDS TO
EUGENE MILLER AND HERMAN BUCHNER, BOTH OF SAME PLACE.

LOCOMOTIVE-JOURNAL LUBRICATOR.

SPECIFICATION forming part of Letters Patent No. 311,744, dated February 3, 1885.

Application filed February 16, 1884. (No model.)

To all whom it may concern:

Be it known that I, ERI GRAHAM, a citizen of the United States, residing at Lancaster, in the county of Grant and State of Wisconsin, 5 have invented a new and useful Locomotive-Truck-Journal-Cellar-Spring, of which the following is a specification.

My invention relates to improvements in packing and lubricating the journals of locomotive-truck wheels. A combination of a spring and saddle is used in place of the cellar-bolt to retain in position the cellar; and the objects of my improvements are, first, to improve the manner of packing and lubricating 15 the journals of locomotive-truck wheels; second, to supply a more speedy and convenient way of packing and lubricating such journals; third, to prevent the loss of cellars; fourth, to supply a more constant lubrication to the journals of such trucks; fifth, to obviate the necessity of using the cellar-bolts. I attain these objects by the improvement illustrated in accompanying drawings, in which—

Figure 1 is the complete improvement, of 25 which b'' is the spring-blade and $a'' a''$ are the saddles attached to the spring-blade b'' . Fig. 2 is one of the saddles a'' detached. Fig. 3 is the cellar-spring attached, showing a view of the inner side of a locomotive-engine truck, 30 and the application of the improvement to the side pedestal of a locomotive-engine truck, and the saddles $a'' a''$ in their proper places, and supporting the cellars without the use of the common bolt.

I prefer to carry out the design of my invention as shown in Fig. 3, viz: The spring-blade b'' is attached by two bolts on the under side of the pedestal of a locomotive-engine truck, the bolts passing through the pedestal 40 one on each side of and about six inches from the longitudinal center of the blade b'' . Out-

side of each bolt a clip or clasp is fastened around the pedestal and spring b'' . These clips or clasps may be moved in or out to regulate the flexibility of the spring. The spring-blade b'' should be of such a length that the saddles $a'' a''$, when adjusted to the ends of the blade b'' , should be immediately under the cellar, the flanges or prongs of the saddles $a'' a''$ on each side of the pedestal and resting in and supporting the cellar at the shoulders. When this improvement is properly attached, the cellar may be packed in the simple manner, as follows, viz: Insert a lever between the outer end of the saddle a'' , Fig. 3, and the pedestal; bear down on the lever sufficiently to let the cellar drop down on the pedestal; keep the spring in this position by inserting between the spring-blade b'' and the pedestal, as near as possible toward the center of the spring, 55 a wedge or hammer-handle; then pack the cellar, remove the wedge or hammer, and the spring b'' by means of the saddle a'' will raise the cellar against the journal.

The superiority of my invention over the 60 old mode of holding the cellar is that by the use of this improvement time and labor are saved in packing the cellars, the breaking of bolts and loss of cellars prevented, and the journals constantly supplied with lubrication, 65 and the heating of journals obviated.

I am not aware that prior to my invention this improvement has been used or made, and therefore claim as my invention and desire to procure Letters Patent on—

The combination of the spring-blade b'' with the saddles $a'' a''$, all substantially as set forth.

ERI GRAHAM.
